UNITED STATES PATENT OFFICE.

CHARLES A. MOORE, OF EDINA, MINNESOTA.

REFRIGERATOR.

Application filed April 22, 1926. Serial No. 103,779.

My invention relates to improvements in refrigerators particularly, though not exclusively, for domestic purposes.

An object of the invention is to provide a simple and efficient refrigerator including simple and effective means for ventilating the same.

A further object is to supply such ventilating means, the same being so associated with the refrigerating medium as to set up ventilation in the refrigerator by gravity.

Another object is to provide ventilating means, as above, arranged to stimulate the circulation of air in the produce compartments, also to minimize humidity from accumulations of condensations therein and, further, to utilize compartment partitions in the structure of said ventilating means.

With the foregoing and other objects in view, which will appear in the following description, the invention resides in the novel combination and arrangement of parts and in the details of construction herein-after described and claimed.

In the drawings, Fig 1 is a vertical central sectional view of a refrigerator embodying my invention; Fig. 2 is a horizontal sectional view thereof, the same being taken on the line 2—2 of Fig. 1 and Fig. 3 is a vertical sectional view taken on the line 3—3 of Fig. 1.

Reference being had to the drawing, it will be observed that my improved refrigerator includes the usual box-like cabinet A comprising a bottom 10, ends 11, front with doors 13 therein, back 14 and top 15, which cabinet is supplied with an inner lining 16 insulated, as at 17, from said parts of said cabinet. Within the cabinet is a hollow partition B, L-shaped in vertical cross section, and consisting of an upright branch b and a horizontal branch b'. This partition B provides a compartment C in an upper corner of a provision chamber D encased by the cabinet. The upper extremity of the upright branch b of the partition B falls short of the top of the cabinet providing an elevated port 18, affording communication between the upper portion of the provision chamber D and the upper portion of the refrigerant compartment C. The extremity of the horizontal branch b' of the partition B falls short of the adjacent end wall of the lining 16 providing a port 19 affording communication between the lower portion of the refrigerant compartment C

and the bay in the provision chamber D beneath said horizontal branch b'.

The upright branch b of the hollow partition B consists of two spaced walls 20 and 21, while the horizontal branch b' of said partitions consists of spaced trays 22 and 23, the upper tray 22 branching off from the wall 20 and the lower tray 23 from the wall 21. These walls 20 and 21 and trays 22 and 23 form between them an air passageway E traversing the interior of the cabinet from front to back. The space between the walls 20 and 21 at the upper edges thereof is spanned by a cap-piece 24 through which the lower end of an upright air ingress duct 25 opens. This duct extends through the top 15 of the cabinet bringing the upper portion of the air passageway E in the partition B into communication with the outer air. Said air passageway E is unobstructed at the extremity of the horizontal branch b' of the partition B, said passageway, at this point, opening into the duct 19 between the refrigerant compartment C and the provision chamber D.

Between the walls 20 and 21 of the partition B is an upright egress duct 26 opening at its upper end near the ceiling of the provision chamber D, the lower end of said duct opening outward through the front 12 of the cabinet into the outer air.

A suitable air chilling medium, (not shown) such as ice or any of the conventional freezing units is placed within the refrigerant compartment C. In the presence of a chilling medium so disposed, an internal circulation of air is set up within the cabinet by gravity, such circulation being accompanied with ventilation, also by gravity, through the ingress of air to the cabinet and the egress of air therefrom. The cycle of the air in its internal circulation within the cabinet may be traced beginning in the refrigerant compartment C, where the air, cooled by the refrigerant, descends by gravity through the port 19 into the provision chamber D. Heated in chamber D by the provisions and along the walls of said chamber, the air rises to the upper portion of the chamber and thence flows through the port 18 into the upper portion of the refrigerant compartment C, whence the cycle is completed. In the present connection, it will be noted that the port 19, disposed along the end wall of the interior of the cabinet, provides for a thorough circulation

of air in that portion of the provision chamber D beneath the refrigerant compartment C, no dead air being permitted to stand in said portion of said chamber. To comprehend the movement of the air in ventilating the cabinet, it must be understood that the wall 20 and tray 22 of the partition B are chilled by the refrigerant in the compartment C. The air in the passageway E, in turn being cooled by said wall 20 and tray 22, flows out of said passageway into the port 19 through which the circulating stream of air is passing the air flowing from said passageway E being replenished with fresh air entering through the duct 25. Co-incident with such ingress of fresh air to the interior of the cabinet is the egress of air therefrom, the same taking place in the egress duct 26. This egress duct being cooled through the wall 20, under the influence of the refrigerant in the compartment C, results in the cooling of the air in said duct 26. Said air thus affected flows by gravity out of the duct 26 to the outside of the cabinet, the same being followed by air entering the upper end of said duct.

The provision of the air passageway E within the partition B is advantageous in that the incoming of fresh air therein in a measure insulates the wall 20 and tray 22 from the wall 21 and tray 23 keeping the former wall and tray comparatively dry and thereby minimizing the percentage of humidity within the cabinet. Further, the wall 21 thus insulated from the wall 20 and affected by the incoming air is relatively warm, the result being that the upward movement of air in the provision chamber D along said wall 21 is stimulated as opposed to being retarded were said wall to be relatively cold.

Condensation accumulating in the lower pan 23 is conducted from the cabinet through a main drain pipe 27. Likewise, condensation accumulating in the upper pan 22 is led away through a stub pipe 28, which empties into said main drain pipe 27.

Changes in the specific form of my invention, as herein disclosed, may be made within the scope of what is claimed without departing from the spirit of my invention.

Having described my invention, what I claim as new and desire to protect by Letters Patent is:

1. In a refrigerator, a cabinet enclosing a provision chamber, a partition, L-shaped in vertical cross-section, providing a refrigerant compartment in an upper corner of said chamber, the upright branch of said partition falling short, at its extremity, of the ceiling of the chamber and the horizontal branch falling short, at its extremity, of an end wall of said chamber, said partition comprising double walls spaced apart to form an air passageway therebetween, also

a cap-piece closing the space between the upper edges of the walls of the upright branch, an upright air ingress duct extending through the top of the cabinet and opening at its upper end into the outer air, the lower end of said duct opening through said cap into said air passageway between said walls, and an upright air egress duct disposed between said walls, said egress duct communicating at its upper end with the provision chamber near the ceiling thereof and opening at its lower end into the outer air.

2. In a refrigerator, a cabinet enclosing a provision chamber, a portion, L-shaped in vertical cross section, providing a refrigerant compartment in an upper corner of said chamber, said compartment communicating at its upper portion with the upper portion of the provision chamber and at its lower portion with a lower portion of said chamber, said partition including spaced walls forming therebetween an air passageway opening into the provision chamber from the horizontal branch of the portion, an ingress duct leading into the structure from without and opening into said air passageway at the upright branch of said partition, and an egress duct disposed between the walls of said upright branch, said egress duct leading from the upper portion of the chamber downwardly and to outside of the cabinet.

3. In a refrigerator, a cabinet enclosing a chamber, for provisions, a partitioning structure within said chamber including an upright branch and a horizontal branch, said partitioning structure providing a refrigerant compartment communicating at its upper portion with the upper portion of the provision chamber and at its lower portion with a lower portion of said chamber, said branches of said structure comprising spaced walls forming an air passageway therebetween opening into the provision chamber from said horizontal branch, an air ingress duct leading from without the cabinet into said passageway at the upper portion of the upright branch of said partitioning structure, and an air egress duct within the cabinet communicating at its upper end with the upper portion of the provision chamber, said duct leading downwardly to outside of said cabinet.

4. In a refrigerator, a cabinet enclosing a chamber for provisions, a partitioning structure within said chamber including an upright branch and a horizontal branch, said partitioning structure providing a refrigerant compartment communicating at its upper portion with the upper portion of the provision chamber and at its lower portion with a lower portion of said chamber, said branches of said partitioning structure comprising spaced walls forming an air passage-

way therebetween opening for the egress of air at the place of communication between said lower portion of said refrigerant compartment and the provision chamber, means 5 for the ingress of air into the upper portion of said air passageway, and an air egress duct within the cabinet communicating at its upper end with the interior of the cabinet near the top thereof and leading downward 10 to the outside of the cabinet.

5. In a refrigerator, a structure providing a provision chamber and a refrigerant compartment, said compartment communicating at its upper portion with the upper portion 15 of the provision chamber and at its lower portion with a lower portion of said chamber, an air ingress duct leading downwardly into said structure from the outside and opening into the interior of the structure 20 at the place of communication between the lower portion of said refrigerant compartment and said provision chamber, and an air egress duct within said structure, the same leading downward to the outside of 25 the structure.

6. In a refrigerator, a cabinet, an upright hollow partition therein providing a compartment for a refrigerant on one side thereof and a chamber for provisions on the other 30 side, said partition being foreshortened at top and bottom to provide for communication between said compartment and chamber

at different elevations, means for the ingress of air from without the cabinet into the space within said hollow partition at the 35 upper portion thereof, said space opening into the interior of the cabinet at the lower portion of said partition, and means for the egress of air from the cabinet, said means being arranged to conduct air from the upper portion of the interior of said cabinet 40 downwardly to the outside thereof.

7. In a refrigerator, a cabinet, an upright hollow partition therein providing a compartment for a refrigerant on one side thereof and a chamber for provisions on the other side, said partition being foreshortened at top and bottom to provide for communication between said compartment and chamber at different elevations, means for 45 the ingress of air from without the cabinet into the space within said hollow partition at the upper portion thereof, said space opening into the interior of the cabinet at the lower portion of said partition, and 50 means, incorporated within said hollow partition for the egress of air from the cabinet, said means being arranged to conduct air from the upper portion of the interior of said cabinet downwardly to the outside 55 thereof.

In testimony whereof, I have signed my name to this specification.

CHARLES A. MOORE.
